UNITED STATES PATENT OFFICE.

CHARLES F. GAUNT, OF BIRMINGHAM, ENGLAND.

MANUFACTURE OF BUTTONS, BADGES, OR THE LIKE.

Application filed September 25, 1922. Serial No. 590,549.

To all whom it may concern:

Be it known that I, CHARLES FREDERICK GAUNT, of the city of Birmingham, England, a subject of the King of Great Britain, have invented certain new and useful Improvements in the Manufacture of Buttons, Badges, or the like; and I do hereby declare that the following is a full, clear, and exact description thereof:

10 This invention relates to manufacture of buttons, badges or the like and is primarily intended to provide means whereby buttons or badges may be made by hand without the use of machinery or sewing, thus 15 providing for the making by the users of buttons of any required shape or size and covered with any required material.

According to the present invention for the manufacture of buttons, badges or the like I provide a disc, plate or foundation member of suitable thin sheet material and at its edges or periphery this member is provided with a number of projections which can be bent to engage and retain 25 the edge of the covering material after which they may be bent backwardly so as to lie at the back of the button, badge or the like so as to be out of sight.

It is preferred to provide the disc plate 20 or equivalent member with a central raised portion of the form required for the face of the button and to provide a stiffening member of suitable form fitting into the under side of this raised portion.

35 This stiffening member is preferably provided with a pin or an eye or otherwise formed to provide for the attachment of the button or badge to the garment by the pin or by sewing and the bent back hook like portions at the periphery of the 40 foundation may engage over its edges.

For full comprehension, however, of my invention, reference must be had to the accompanying drawings in which similar 45 reference characters indicate the same parts and wherein:

Figure 1 is a fragmentary plan view of the foundation member of the button;

Figure 2 is a similar view of the button 50 when the projections of the foundation member have been folded inwardly to grip the covering material;

Figure 3 is a sectional elevation of the member shown in Figure 1;

55 Figure 4 is a sectional elevation of the button as shown in Figure 2;

Figure 5 is a sectional view showing the button in the next stage of formation;

Figure 6 is a sectional view showing the button in the next stage of formation; and

Figure 7 is a part sectional view showing the final form of the button.

In the construction illustrated upon the accompanying drawings the base member 1 is formed of thin sheet metal and is circular in shape, being provided with a raised central dome like portion 2. At its periphery it is provided with a large number of substantially radial projections 3 formed by slotting out the material between them. The outer ends of these projections 3 are forked and the points 8 bent inwardly so that in use a good grip of the covering material is ensured.

The base member is provided with a stiffening member 4 of such a shape as to fit closely into the inside of the dome shaped portion 2. A central depression 5 is formed in each of the two members 1 and 4 to take a metal disc 6 to which an eye member 7 is adapted to be secured, the shanks of the eye member passing through suitable holes in the members 1 and 4. This eye member 7 is used in attaching the button in its required position on a garment.

When it is required to form a button covered with any desired fabric material, a piece of the said material is cut to the required shape and laid on the base 1 as shown in Figures 1 and 3. The claw like ends 8 of the projections 3 are then bent inwardly downwardly into engagement with the material 9 and the button now presents the appearance shown in Figures 2 and 4. The periphery thereof is now bent downwardly about the periphery of the stiffening member 4 so as to get the arrangement shown in Figure 5. The downwardly projecting rim 10 is then bent inwardly through the position shown in Figure 6 until it is finally in contact with the inner surface of the member 4 as shown in Figure 7.

In a modified construction no stiffening member is used, the base member being shaped so as to leave a central recess at the back, and when the covering material has been gripped by the projections the periphery is bent downwardly and inwardly about a disc like member placed in the aforementioned recess and so retains this disc like member in position. The disc like member is provided with an eye or pin or

other suitable means by which the button may be secured to a garment.

It will be understood that this invention is applicable to any shapes and sizes of buttons, badges or the like either for use or adornment, and provides a simple means whereby the users may make their own buttons or badges, using if required in the case of buttons as covering material therefor, the same material of which the garment is made.

What I claim is as follows:

1. The method of manufacturing buttons consisting in forming a sheet metal disc 15 with a plurality of spaced radial projections on its periphery mounting the disc upon a stiffening member of dome form and making it conform thereto mounting a piece of fabric upon the disc, turning the projections 20 up and back upon the fabric and folding the edge thus formed and which protrudes beyond the stiffener beneath the latter.

2. A button consisting of a sheet metal stiffening member of dome form, a relatively 25 flexible base member mounted upon the stiffening member and of larger dimensions than the latter, said base member having a plurality of radial projections bent up and back upon itself and adapted to retain a 30 piece of fabric thereon, the edge thus

formed with the portion of the fabric gripped thereby being bent beneath and upwardly within the stiffening member presenting a fabric top having an unbroken surface.

3. A button consisting of a stiffening member of concavo-convex cross section, a relatively flexible base member mounted upon the convex side of the stiffening member and conforming thereto, said members having a central depression; means for securing the members together and for attaching the button to an article, said means consisting of a disc mounted in the depression in said members and an eye located beneath the members and passed therethrough and connected to the disc, said base member having a plurality of spaced radial projections on its periphery turned up and back upon itself and adapted to retain a piece of fabric, and the peripheral edge of the base member with the portion of the fabric gripped thereby being bent beneath the stiffener member.

In testimony whereof I have signed my name to this specification in the presence of two witnesses.

CHARLES F. GAUNT.
